ADHESIVE DISPENSING RECEPTACLE

Eugene J. Ray, Beverly, Mass., assignor to United
Shoe Machinery Corporation, Paterson, N. J., a
corporation of New Jersey

Application May 13, 1933, Serial No. 670,908

19 Claims. (Cl. 91—67.1)

This invention relates to receptacles for dispensing adhesive and is illustrated as of the type in which an inverted supply tank is used to maintain adhesive at a constant level in a receptacle from which it is dipped.

In shoe factories, for example, it is common for an operator to take a saucer full of adhesive such as latex and to dip a hand brush in this saucer as he utilizes the adhesive. Such an arrangement is subject to the disadvantages that the adhesive is apt to become filled with dust or other loose dirt and that evaporation is so rapid that, in the case of latex, the adhesive tends to coagulate.

In accordance with a feature of the invention the exclusion of dirt and the prevention of evaporation are facilitated, in the illustrated construction, by an arrangement including a hinged cover provided with a spring to hold it either in closed or in open position. Preferably and as shown, this cover is subdivided with the forward portion hinged to the main cover and with a spring interconnecting the two cover portions which is arranged to hold them in alignment or to support the forward cover portion in open position.

In the drawing,

Fig. 1 is a side elevation, with parts broken away and in section, of the dispensing receptacle;

Fig. 2 is a plan view with the cover in closed position;

Fig. 3 is a fragmentary view in elevation showing the cover in open position; and

Fig. 4 is a similar view with only the forward cover portion open.

A tray-like receptacle 10 supported upon the legs 12 and 14 has a dipping portion 16 which is somewhat deeper than the rear portion 18 to which the adhesive is supplied from an inverted tank 20. This tank may take any convenient form but is herein shown as a glass jar having a neck 22 to which is secured a bail 24 having a wooden handle 26. This jar is supported on the receptacle by means of an upstanding metal cage 30 which may be made integral with the receptacle and which is cut away at 32 to admit the bail and handle. The provision of a handle renders the jar easier to handle if a considerable quantity of adhesive, such as a gallon, is to be supplied. By having the cage cut away at 32 the operator is able to support the tank 20, by grasping the handle and by taking hold of the jar at the upper opposite side in the position shown continuously, until the jar touches the receptacle. The neck of this jar may be provided with a cap

and valve mechanism 34 such as is shown in an application Serial No. 574,388, filed November 11, 1931, in my name, for Letters Patent for Improvements in closure for receptacles. A packing strip 36 helps to make the receptacle more nearly 5 air-tight when the jar is in place.

The dipping portion 16 of the receptacle is partially separated from the higher portion 18 by a depending partition 38, thereby still further improving the device as regards the exclusion of 10 dirt and the prevention of evaporation. The lower end of this partition extends below the level at which the adhesive is maintained in the receptacle by the inverted tank 20. In the dipping receptacle is provided a cross rod 40 against 15 which a brush may be wiped to remove surplus adhesive.

The dipping portion 16 of the receptacle has a delivery opening at the top having an upper edge inclined downwardly to the front against which 20 seats a rib 42 on the under side of a cover 44. The main portion of this cover is hinged to the receptacle by means of a transverse pin 46 which is adjacent to and above the partition 38, and a coiled tension spring 48 is provided which extends 25 between a lug 50 on the cover and a hook 52 on the side of the receptacle. This spring is so arranged that it will hold the cover either in the closed position shown in Figs. 1 and 2 or in the extreme open position shown in Fig. 3 where a 30 pintle rod 56 contacts with the cage 30. This action results from the fact that the spring passes the hinge axis as the cover is turned from one position to the other. In order that it may not be necessary to open the whole cover if, for example, only a small brush is to be used, a forward subdivided portion 54 of the cover is hinged to the main cover by means of the pintle rod 56 passing through upwardly extending lugs 58 on the main cover and lugs 60 on the forward portion. 40 A coiled tension spring 62 lying substantially in the plane of the cover is connected between the lug 50 on the main cover and a lug 64 on the forward portion. The two portions of the cover are normally maintained rigidly in 45 alignment, as determined by the abutting edges of the two portions, by the tension of this spring 62. When, however, the forward portion 54 is raised into the position shown in Fig. 4, then the spring 62, having passed the hinge axis determined by the pintle 56, holds the forward portion 50 in open position as well. This open position is at a sharp angle to the main cover and is determined by the length of the wholly collapsed spring 62 which then acts like a substantially rigid strut 55

interconnecting the lugs 50 and 64 to support the cover in this open position.

In the use of the device, assuming that the tank 20 filled with adhesive has been inverted 5 into the position shown, either half or the whole of the cover will be opened to permit the introduction of a brush, sponge, or other applying device. If, owing to temporary cessation of use of the device, it is desired to leave a brush 66 in 10 the dipping portion 16 of the receptacle, then the cover may be almost closed and the forward portion 54 held by the spring 62 against the handle of the brush, as shown in Fig. 1.

Having thus described my invention, what I 15 claim as new and desire to secure by Letters Patent of the United States is:

1. In a dispensing device for cements, a receptacle, a support on the receptacle for holding an inverted supply tank in position to supply the receptacle, said receptacle having a top opening at one side of said support, a cover for said opening hinged to the receptacle, and a spring constructed and arranged to hold said cover either in a closed position against the top of the receptacle or in an open position against the support for the tank.
2. In a dispensing device for cements, a receptacle having an opening, a plurality of hinged cover sections adapted to close said opening, and 30 a plurality of springs for controlling the positions of said cover sections.

3. In a dispensing device for cements, a receptacle having an opening, a plurality of cover sections one of which is hinged to the receptacle 35 and the other of which is hinged to the first section, and a plurality of springs associated with said cover sections to control the relation of the cover sections to one another and to the receptacle.

4. In a dispensing device for cements, a receptacle having an opening, a cover hinged on said receptacle adapted to close said opening, said cover being divided and provided with a forward portion hinged to the main cover, and 45 a spring to hold said forward cover portion yieldingly in contact with an article such as a brush in the receptacle.

5. In a dispensing device for cements, a receptacle having an opening, a cover hinged on 50 said receptacle adapted to close said opening and provided with a forward portion hinged to the main cover, and a spring to hold said forward cover portion in alinement with the main cover.

6. In a dispensing device for cements, a receptacle having an opening, a cover hinged on 55 said receptacle adapted to close said opening and provided with a forward portion hinged to the main cover, a spring to hold said forward cover portion in alinement with the main cover, and 60 a spring arranged to hold said main cover in either an open or a closed position.

7. In a dispensing device for cements, a receptacle having an opening, a cover hinged on 65 said receptacle adapted to close said opening and provided with a portion hinged to the main cover, and a spring to hold said cover portion at an angle to the main cover.

8. In a dispensing device for cements, a receptacle having an opening, a cover hinged on 70 said receptacle adapted to close said opening and provided with a portion hinged to the main cover, a spring to hold said cover portion at an angle to the main cover, and a spring to hold said main cover in either open or closed position.

9. In a dispensing device for cements, a re-

ceptacle having an opening, a cover hinged on said receptacle adapted to close said opening and provided with a portion hinged to the main cover, and a spring connecting the main cover and the portion arranged to hold the portion either in closed position or in an open position at an angle to the main cover.

10. In a dispensing device for cements, a receptacle having an opening, a cover hinged on 10 said receptacle adapted to close said opening and provided with a forward portion hinged to the main cover, and a coiled tension spring extending between the main cover and the forward cover portion, said spring being of a length such that it becomes wholly collapsed when the forward cover portion is tipped back upon the main cover and being arranged to hold said forward cover portion either in a closed position or in an open position determined by the collapsed position of the spring.

11. In a dispensing device for cements, a receptacle having a delivery opening, a hinged cover for said opening having a forward portion hinged to the main cover, means for limiting the turning movement of the forward portion at a 25 point where it is in alinement with the main cover, and a tension spring extending between the main cover and the forward portion to hold the said portion normally in this alined position while permitting the user to open either the forward portion alone or the whole cover as a rigid unit.

12. In a dispensing device for cements, a receptacle having an opening, a hinged cover for said opening having a portion hinged to the main 35 cover, means for limiting the turning movement of the portion at a point where it is in alinement with the main cover, a tension spring extending between the main cover and the portion to hold the portion in this alined position, and a spring 40 arranged to hold the main cover in either open or closed position.

13. In a dispensing device for cements, a receptacle having an opening, a cover hinged on said receptacle covering said opening and provided 45 with a forward portion joined to the main cover by an offset pintle rod, means including a spring interconnecting the main cover and the forward portion and extending at one side of the pintle rod substantially in alinement with the cover 50 portions to hold the forward portion in such alined position, and a spring secured at one end to said receptacle and at the other end to the main cover constructed and arranged to pass the hinge axis as the cover is opened thereby to hold 55 the cover either in closed or in open position.

14. In a dispensing device for cements, a receptacle having an opening, a hinged cover for the opening of said receptacle divided along a line parallel to the hinge axis, a pintle rod connecting the forward portion and the main cover offset from the plane of the cover, and a spring interconnecting the forward portion with the main cover constructed and arranged to pass the axis of the pintle rod thereby to hold the forward portion either in alined position or in a position at a sharp angle with the main cover.

15. In a dispensing device for cements, a tray-like receptacle the forward portion of which is open at the top, said receptacle having a cage- 70 like support at the rear of said top opening for the purpose of holding a supply tank for the receptacle, a cover for said top opening hinged adjacent to said cage-like support and adapted when open to contact therewith, and a spring se- 75

cured to said receptacle and to said cover, said spring being positioned to pass the hinge axis as the cover is opened and constructed and arranged to hold the cover either in closed position against the top of the receptacle or in open position against the cage-like support.

16. In a dispensing device for cements, a tray-like receptacle divided into a forward portion and a rear portion by a partition the lower edge of at least a portion of which is spaced from the bottom of the receptacle, said receptacle being provided with means for supporting a supply tank at one side of said partition and having a top opening at the other side of said partition the edges of which are inclined downwardly toward the front, a hinged cover for said receptacle pivoted upon an axis adjacent to and above said partition, and a spring connected to the edge of said cover forward of said axis and connected to the side of the receptacle to the rear of the axis at a point such that the spring will pass the axis as the cover is opened and will thereby hold the cover in an open position or in a closed position.

17. In a dispensing device for cements, an open-topped receptacle, a hinged cover pivoted at a point removed from the front edge of the top opening, said cover being divided in two parts along a line substantially parallel to the axis of said hinge with its edges in abutting relation when the two parts of the cover are substantially in alinement, a hinge connecting the two parts of the cover comprising a pintle rod positioned above the plane of the top of the cover, and a coiled spring connected to the two parts of the cover and arranged, when the cover parts are in alinement, to lie below the pintle rod, said spring being disposed above the pintle rod when the forward cover part has been opened.

18. In a dispensing device for cements, an open-topped receptacle, a hinged cover pivoted

away from the front edge of the top opening, said cover being divided into two parts along a line substantially parallel to the axis of said hinge with its edges in abutting relation when the two parts of the cover are in alinement, a hinge connecting the two parts of the cover and comprising a pintle rod positioned above the plane of the top of the cover, and a coiled spring connected to the two parts of the cover and arranged, when the cover parts are in alinement, to lie below the pintle rod, said spring being disposed above the pintle rod when the forward cover part has been opened, the length of said spring being such that it becomes wholly collapsed and thereby forms a substantially rigid strut to hold the forward cover portion in raised position.

19. In a dispensing device for cements, a tray-like receptacle provided with an incomplete depending partition dividing the forward portion from the rear portion, the rear portion of said receptacle being provided with an upstanding hollow cage adapted to receive an inverted supply tank, the forward portion of said receptacle having a top opening, a two-piece cover normally closing said receptacle, said cover being hinged to the receptacle along its rear edge, the adjacent edges of the parts of said cover abutting one another when the cover is closed, said cover parts being joined by a hinge comprising a pintle rod above the plane of the cover, a spring lying substantially in the plane of the cover and joining the two parts thereof, and another spring connected to the receptacle and joined to the cover, said latter spring being arranged to pass the hinge axis as the cover is opened thereby to hold the cover either in closed position or in an open position with the pintle rod touching the upstanding cage.
